UNITED STATES PATENT OFFICE

ALLEN F. RUFFIN, OF WATERBURY, AND ARTHUR L. WECKLER, OF THOMASTON, CONNECTICUT, ASSIGNORS TO SCOVILL MANUFACTURING COMPANY, OF WATERBURY, CONNECTICUT, A CORPORATION OF CONNECTICUT

ATOMIZER SUPPORT

Application filed May 23, 1928. Serial No. 279,872.

This invention relates to certain improvements in atomizers, and particularly to the base or support for holding the substance to be atomized.

Atomizers as generally constructed include a support capacitated to hold the perfume or other liquid which is to be atomized, the atomizing mechanism proper, and the bulb or the like by which the atomizing operation is effected. For practical use these atomizers have to be of sufficient dimensions so that the support will be maintained in an upright position and will carry the atomizing mechanism. It is frequently desirable to dispense from an atomizer certain perfumes which are so expensive that they can be used in small quantities only, these quantities being so small as to make their use in ordinary atomizers impracticable.

It is the especial object of the present invention to provide a support for the atomizer which is capacitated to hold but a small quantity of the perfume or essence to be atomized and which at the same time is so arranged that the atomizing mechanism will function properly, and which is sufficiently rigid and of sufficient dimensions to properly support such mechanism.

A further object of the invention is to produce an atomizer and support of few parts and simple form so that it can be cheaply made and quickly assembled and so arranged that the essence to be dispensed may be readily positioned in the support.

With these and other objects not specifically referred to in view, the invention consists in certain novel parts, arrangements and combinations which will be described in connection with the accompanying drawings and the novel features pointed out in the claims hereunto appended.

In these drawings,—

Figure 1 is a side elevation of the improved atomizer, and

Figure 2 is a central vertical section looking in the direction of arrow 2 of Figure 1.

Referring now to these drawings, the improved support will include, preferably, a wide flat base 1 and a head 2 supported from the base. While the head may be supported

in various ways, in the particular construction illustrated there is provided a thin stem 3 having a reduced lower end 4 which passes through a hub 5 soldered or otherwise secured to the upper part 6 of the base, the stem being held in position by heading up the end 4 of the stem as indicated at 7, a washer 8 being provided, if desired, between the part 6 of the base and the head 7. The base in the particular construction illustrated comprises, as shown, the flat part 1' and the upper part 6, and these may be secured together in any suitable manner, as by turning the edge of the part 6 in under the flat part 1' as indicated at 8'. The upper end of the stem 3 is likewise reduced and this reduced portion is threaded as at 9 to receive a lock-nut 10, the reduced end of the stem passing through an opening 11 in the bottom of the head 2. If desired, a washer 12 may be introduced between the stem and the end of the head.

In accordance with the invention, this construction affords a firm rigid support for the atomizing mechanism hereinafter referred to. In accordance with the invention, the head is adapted to carry an essence holder of relatively small capacity which is positioned so that it will be in proper relation with the atomizing mechanism before the latter can properly effect its function.

While this essence holder may be of various characters and held in position in various ways, in the particular construction illustrated the top of the head is provided with an aperture 13 in which is set a threaded neck 14, this neck being preferably held in place by turning in the edges 15 of the neck beneath the edge of the head surrounding the opening. Arranged to be secured in this neck is an essence holder shown in the form of a small bottle 16 having a flange 17 by which it may be screwed into the neck 14, the bottle thus depending in the head as clearly shown in Figure 2.

While the neck may receive an atomizing mechanism direct, in the best constructions the neck is closed by a cap 18 which has a depending threaded central flange 19 into which the atomizing mechanism may be threaded so as to be in correct relation with

the essence holder 16. The cap may be held in position on the neck in various ways, as by friction, so that it can be removed therefrom for renewing the supply of essence, or if desired it may be secured by lightly cementing it to the neck.

The atomizing mechanism may be of any usual or standard type, including the atomizer 20, pipe 21, and bulb 22.

10 The parts may be assembled in any convenient or desired manner. For ease in assembling, however, the head 2 is made in two parts, secured together by turning the edge of one of the parts over the edge of the other, 15 as indicated at 23 in Figure 2. The nut 10 and the stem 3 may be first secured together, the neck 14 secured to the upper part of the head 2, and then the two parts of the head secured together. The essence holder may then 20 be screwed into position and the cap 18 positioned on the neck as described.

It will be seen that with the construction described the support is of sufficient dimensions and rigidity to properly support the 25 atomizing mechanism, but at the same time provision is made for a small supply of the essence to be dispensed, and thus the desired use of highly priced essences or perfumes in an atomizer may be obtained.

30 While the invention has been shown and described in its preferred form, it will be understood that certain changes and variations may be made in the specific construction shown and described without departing from 35 the invention as defined in the appended claims.

What is claimed is:

1. In an article of the character described, 40 the combination of an essence holder of such small size as to require other support than itself, a casing into which the holder depends, a threaded neck secured to the casing into which neck the holder is threaded, a cap closing the neck, an atomizer connected with 45 the casing and in communication with the holder, and a base dimensioned to support the casing and atomizer in an upright position.

2. In an article of the character described, 50 the combination of a casing dimensioned to be readily handled, an essence holder of such smaller size as to require other support than itself positioned in the casing, an atomizer connected with the casing and in communication with the holder, a base dimensioned to 55 support the casing and atomizer in an upright position, and a stem between the base and holder of smaller dimensions than either and forming a convenient handle when using the article.

3. In an article of the character described, 60 the combination of an essence holder of such small size as to require other support than itself, a casing into which the holder depends, a neck having an inturned flange by 65 which the neck is rigidly secured to the cas-

ing, a flange on the holder arranged to engage frictionally with the inner wall of the neck, a cap closing the neck, an atomizer connected with the casing and in communication with the holder, and a base dimensioned to 70 support the casing and atomizer in an upright position.

In witness whereof, we have hereunto set 75 our hands.

ALLEN F. RUFFIN.
ARTHUR L. WECKLER.
